STEAM IRON

Robert J. Scott, Blue Springs, Mo., assignor to
 John C. Hockery, Kansas City, Mo., as trustee
 for Henry J. Talge and Foster L. Talge

Application July 7, 1949, Serial No. 103,339

13 Claims. (Cl. 38—77)

1

The present invention relates in general to flat irons for pressing fabrics and it deals more particularly with the construction of an improved type of electrically heated steam generating iron.

The electric steam generating irons heretofore developed fall into two general classifications, each having certain advantages over the other, and each having corresponding disadvantages. First, there is the "tea kettle" type of steam iron wherein a relative large body of water contained in the iron is heated (usually by the same electrical element which heats the sole plate) the steam formed above the surface of the water being conducted through suitable ducts onto the fabric being ironed. Secondly, there is the "flash boiler" type wherein water stored in a reservoir is fed drop by drop onto a hot plate, the individual drops thereby being flashed into steam in a more or less continuous succession and the steam being fed onto the fabric as it is generated.

One of the shortcomings of the tea kettle type of unit is that so long as it contains water it must be used as a steam iron; it is impossible, in other words, for the operator to shut off the flow of steam at will and use the iron as a conventional "dry" iron.

Another disadvantage lies in the necessity of bringing the entire body of water to the boiling point before any steam is generated. Thus, starting with a cold iron and cold water there inevitably is considerable delay in obtaining steam; likewise, when the heating element is turned off after a period of operation, the steam continues to issue from the iron for an undesirable interval due to the stored heat. Whatever heat has been stored in the body of water when the element is turned off is, of course, lost without serving any useful purpose.

Added to this inefficiency and the sluggishness in starting and stopping steam generation, the tea kettle type of iron presents an exceedingly difficult problem of thermal design owing to the fact that the entire body of water must be heated to the boiling point. Obviously, this requires heat transfer of high efficiency and considerable magnitude, conditions which are difficult to meet in practice, having proper regard for economic considerations and other design requirements. Especially critical does the problem become when the iron is to be operated at the relatively low sole plate temperatures that must be used in order to avoid scorching celanese and like synthetic fabrics when these are ironed. All practical irons of this character developed in the past therefore have involved certain compromises and

2

sacrifices in design in order that moderately successful operation might be obtained at a reasonable cost.

Most of these difficulties and shortcomings are obviated in the flash boiler type of unit. In the latter because the entire body of stored water is not heated, it is possible to obtain steam very quickly and to shut it off quickly at will. Also because the amount of water being heated at any given instant is small, it is not difficult to obtain steam even at low sole plate temperatures.

Despite these apparent advantages, the tea kettle type of iron still is the more widely used of the two due to certain new difficulties introduced in the case of the flash boiler type of iron. For example, the rate at which the water is allowed to drip onto the hot plate in the latter is quite critical and must be regulated in accordance with the temperature of the plate; this 10 temperature varies as the sole plate temperature is adjusted for ironing different fabrics and thus far no satisfactory arrangement for correlating the rate of feed and the temperature of the sole plate has been developed. Also there often is a 15 tendency for a drop of water upon striking the hot plate to spatter or roll sizzlingly across the surface of the plate without flashing into steam, and, in many instances, the steam issuing from the iron contains a large amount of entrained 20 globular water which, of course, is objectionable in that it will spot many fabrics. Customarily a needle valve is used to regulate the feeding of water onto the hot plate and this likewise is a 25 frequent source of trouble by virtue of becoming clogged or improperly adjusted. Another difficulty is that the needle valve must be closed whenever the heating element is turned off, and in practice the irons often are flooded due to 30 failure of the operator to take this precaution.

It is the purpose of the present invention broadly speaking, to provide a new type of iron which has the advantages of both types outlined above but is free from their respective disadvantages. An important feature resides in the provision of a steam generator, novel in construction 35 and operation.

More specifically, one of the objects is to provide an iron which will generate steam very quickly after being connected, and will cease 40 generating steam quickly when the heat is turned off; another object is to make it possible to use the unit as a steam iron or a dry iron at will without the necessity of removing the water therefrom.

A further object is to provide a steam iron

55

which heats only a relatively small amount of water at a time and hence will generate steam even at relatively low sole plate temperatures, yet which is free of troublesome feed valves, valve adjustments, spattering and the other difficulties present in the flash boiler type of iron.

Another object is to provide an iron of high thermal efficiency both from the standpoint of the transfer of heat to the water for generating steam and also from the standpoint of minimizing loss of stored heat at the close of an ironing operation.

Still another object is to provide an iron of the character indicated above which is simple and economical to manufacture and service, which is rugged, durable and trouble free in operation, and which is attractive in appearance.

Other and further objects of the invention together with the novel features of construction whereby objects are achieved, will appear in the course of the following description.

In the accompanying drawings which form a part of the specification and are to be read in conjunction therewith, and in which like reference numerals are employed to indicate like parts of the various views:

Fig. 1 is a plan view of a steam iron embodying my invention, part of the handle and housing being cut away for purposes of illustration.

Fig. 2 is a cross sectional view taken along the line 2—2 of Fig. 1 in the direction of the arrows.

Fig. 3 is a fragmentary cross sectional view taken along the line 3—3 of Fig. 2 in the direction of the arrows.

Fig. 4 is a fragmentary cross sectional view taken along the line 4—4 of Fig. 1 in the direction of the arrows.

Fig. 5 is a cross sectional plan view taken along the line 5—5 of Fig. 2 in the direction of the arrows.

Fig. 6 is a view of the bottom or under side of the sole plate of my iron.

Fig. 7 is an enlarged cross sectional view showing in detail the arrangement for sealing together the upper and lower parts of the iron when the two are in assembled condition, and

Fig. 8 is a view similar to Fig. 7 illustrating a modified form of construction.

Referring more particularly to the drawings, my iron has a sole plate 10 with a U-shaped resistance heating element 12 embedded therein. Conveniently the sole plate is cast of aluminum or other metal having suitable thermal conductivity. In order to heat the sole plate, electrical connections, not shown, are made to upstanding insulated terminals or binding posts 14 at the rearmost extremities of the legs of the resistance element. Its temperature is controlled thermostatically by means of a bi-metal blade 16 secured to the sole plate, this blade cooperating with a pair of contact springs 18 and 20 which together form a switch wired in series with the heating element in conventional fashion.

As will be clear from the drawings, the aforementioned contact springs are mounted on insulators 22 in a longitudinal recess 24 located at the rear end of the sole plate between the two legs of the heating element. Also mounted on the insulators by means of an offset arm 26 is a stationary nut 28 which supports a threaded shaft 30. A finger 32 of insulating material secured to the lower end of the shaft extends through an aperture in the upper spring 18 and engages the lower spring 20; thus by turning knob 34 spring 20 may be adjusted up or down to regulate the

temperature at which the contacts will be opened and closed by the bi-metal element 16. This method of regulating and maintaining the temperature of the sole plate automatically is conventional, and forms no part of the present invention.

Forwardly of the bi-metal element is a small boiler or steam generator 35 comprising an arched cover 36 which is flanged about its periphery and secured to the upper side of the sole plate by screws 38. Preferably the flange is sealed to the sole plate by a gasket material such as an inorganic silicon elastomer applied to the underside of the flange before it is screwed down.

15 The forward portion of the cover is provided with a dome 40 for receiving the upper end of a tube 42 through which steam may pass downwardly onto the fabric being ironed. The lower end of the tube is threaded into the sole plate and 20 communicates with the triangular recess 44 in the underside of the sole plate, this being covered by a plate 46 flush with the ironing surface, which plate is provided with steam outlet orifices 48 arranged in any desired pattern. Attached by 25 screws as shown, the plate 46 is maintained spaced from the bottom of the recess by a rim or boss 50.

Spaced above the sole plate is a water reservoir 52, which comprises a hollow shell or housing 54 with a plate 56 covering the bottom and 30 suitably sealed about its margin to the shell. Shell 54 conveniently may be a die casting or may be molded of phenolic resin or the like. A handle 58 is formed integral with the shell or housing and at the forward end of this is a filler opening 60 provided with a closure 62 which presently will be described in detail.

The reservoir is detachably mounted on the sole plate by means of three downwardly extending posts 64 on the reservoir that are insertable into three registering hollow studs 66 on the sole plate. The studs have threaded shanks which are screwed into tapped holes in the sole plate as shown; the pins likewise are threaded at their upper ends and screwed into the housing 54, lock nuts 68 being provided to anchor the pins to the housing and also to assist in fastening the bottom plate 56 to the housing. When the pins have been inserted into the hollow studs they are secured by means of screws 70.

To enclose the space between the bottom of the water reservoir and the top of the sole plate a rabbet is provided around the front and sides of the latter, and a band or skirt 72 conforming with the exterior contour of housing 54 is mounted therein; at the rear of the housing the ends of this skirt turn inwardly and are formed into loops 74 to receive shoulder screws 76 which extend into the sole plate to hold the skirt in place. The fastening screws, as well as the working parts and wiring disposed rearwardly of the skirt, are concealed by an inclined cover plate 78, the upper edge of which fits into a notch 80 in the housing while the lower edge is secured by screws 82 threaded into upturned lugs 84 on the heel rest 86. The heel rest comprises a plate fastened by screws 88 to the sole plate and extending rearwardly thereof.

70 Centrally disposed in the upper surface of the sole plate is a shallow well or pocket 90 which may be circular as shown or of any other desired shape e. g. rectangular or oval. This, it will be noted, is within the boiler under the arched cover 36, and is straddled by the legs of

the heating element 12, with the walls of the well in close proximity to the heating element.

Forward of the well is a floor plate 92 apertured to fit over tube 42 and fastened by a nut 94. This plate conforms in outline with the interior walls of the boiler cover 36, and its forward portion is elevated above the sole plate by a spacing washer 96, it being seen that the plate inclines downwardly to the rear and terminates in an upstanding flange 98 forming a baffle at the edge of the well. The ends of the baffle are spaced slightly inward from the sides of the cover 36 leaving openings 100 through which liquid may drain from the floor plate back onto the sole plate around the well. The purpose of the floor plate and baffle will be explained presently.

Directly over the well is an aperture 102 in the top of the boiler 35, and registering with this is an aperture 104 in the bottom of the water reservoir. A tube 106 forms a duct from the reservoir to the well, the lower end of the tube being spaced above the bottom of the well but below the top. The tube may be constructed to pass freely through hole 102, its upper end being flared outwardly and brazed or otherwise affixed to the margin of hole 104 as shown in Figs. 2 and 7; alternatively, the fired upper end of the tube may be secured to the margin of hole 102 as shown in Fig. 8 in which case the bottom of the reservoir around hole 104 is rolled downwardly. In either case, a resilient deformable O-ring 108 is employed to seal the parts together, this preferably being formed of a heat resisting silicone elastomer. The ring is seated in an annular centering depression 110 in the boiler cover 36, and in the Fig. 7 construction it will be understood that it prevents leakage of steam through the clearance between tube 106 and hole 102; in the Fig. 8 construction the ring prevents any leakage of the water entering the tube through aperture 104.

Above the upper end of the tube is a disk-like closure valve 112 operable at will to prevent the passage of water downwardly from the reservoir into the well. This valve is secured by a screw to the lower end of a rotatable shaft 114, which has a manual control knob 116 at its upper end. On the under side of the knob is a projecting boss 118 which rides on an inclined annular track 120 in the housing 54, a coiled spring 122 around the shaft always serving to urge the shaft, valve and knob downwardly. On rotating the knob approximately one-half turn, the boss 118 travels down the inclined track and valve 112 closes the passageway, it being seen that the valve seats directly on the tube 106 if the Fig. 7 construction is employed, whereas it seats on the depressed margin of aperture 104 if the Fig. 8 construction is employed. When the knob 116 is rotated back to the position shown, it not only opens the passageway to the well, but also seats against the bottom of the protuberance 124 in the housing thereby preventing any leakage of moisture upwardly around the shaft.

Around the opening 104 are a pair of upstanding arcuate baffles 126 and 128. As best seen in Fig. 3, these are of different diameters and overlap one another to a certain extent so that they completely encircle the opening; however, any water in the reservoir may readily flow through the space between the baffles in order to drain through the opening.

Returning now to the closure 62, this comprises a deformable disk of rubber or the like disposed

between a pair of washers 130. A stem 132 having an enlarged head 134 below the lowermost washer is threaded through the center of the washers and the disk so that its upper end protrudes above the upper washer. Straddling the upper end of the stem is the bifurcated end of a lever 136 which is adapted to lay in a groove 138 in the handle 58. The lever is connected to the stem by a pivot pin 140 and its forward end is rounded in eccentric 10 relation to the pivot pin to form a camming surface.

In its normal unrestrained condition, disk 62 is slightly smaller than the filler opening; however, when lever 136 is positioned as shown, the 15 disk is squeezed between the washers 130 so that it expands outwardly and tightly engages the wall of the opening to seal the opening and hold the disk in place. In order to fill the water reservoir, lever 136 is swung upwardly about its 20 pivot pin as indicated by the arrow 142. This permits washers 130 to move slightly apart releasing the pressure on disk 62 which now restores to its normal diameter and can be withdrawn easily from the filler opening. During the 25 filling of the reservoir, the outlet from the reservoir to the well 90 is sealed by closure valve 112 as hereinbefore described. The reservoir may be partially filled as shown or completely filled, and in the latter case, the water rising in the hollow cavity 144 of the rear handle post forces the 30 air above the surface out of a bleeder tube 146 in the handle. Having been filled to the desired extent, the reservoir is resealed by inserting closure 62 into the mouth of the filler opening and 35 swinging lever 136 down to the position shown thereby to expand the closure as explained.

Knob 116 now is turned in order to elevate valve 112 and thus open the outlet from the reservoir. When this is down the water descends 40 in tube 106 filling well 90 to the point where it covers the open lower end of the tube. With the lower end of the tube covered, it is impossible for air to enter the reservoir and hence no additional water will leave the latter.

When the heating element 12 is turned on, the water in the well is heated to the boiling point and the resultant steam passes over baffle 98, up into dome 40, thence down tube 42 and out of orifices 48 onto the fabric being ironed. As the 45 water in the well boils away it automatically is replenished from the reservoir, for whenever the level in the well drops below the end of tube 106, air can enter the lower end of the tube and pass upwardly into the reservoir displacing and 50 releasing a small amount of water into the well. 55 At no time, however, will the level in the well rise materially above the end of tube 106.

When the supply of water in the reservoir becomes very low, there is a tendency for it to 60 surge back and forth across the mouth of opening 104 as the iron is moved in the course of normal pressing operations. To minimize this, and to prevent the opening from at times being completely uncovered as the water travels away therefrom, baffles 126 and 128 are provided around 65 the opening.

Baffle 98 similarly prevents water in well 90 from rushing forward, for example when the iron is drawn backward rapidly. Due to the brisk boiling 70 which occurs in the well, it nevertheless is inevitable that small globules of water sometimes pass over the baffle 98 and descend on the floor plate 92. If the boiling were to continue in this region, water globules might occasionally spatter 75 upwardly and enter the tube 42. To prevent this

and eliminate the possibility of entrained moisture from reaching the fabric being ironed, the floor plate is separated from the sole plate by an air space and thus is maintained cool enough to minimize boiling around the base of the tube 42; also it is sloped downwardly toward the rear so that moisture reaching it drains back through the openings 100 to a point behind the baffle 98. Any spattering which occurs in the latter region is too far from tube 42 to carry any water into the tube.

The amount of water in the well is so small that even when the sole plate is operated at relatively low temperatures there is no difficulty in heating the water and generating steam. Moreover the water is raised to the boiling point very quickly; starting with a cold iron and cold water from the tap, it has been found that steam begins to issue from the orifices in the sole plate in approximately 30 seconds after the heating element is turned on. This obviously is much faster than would be possible if the whole body of water had to be heated, as is the case in conventional "tea kettle" type irons. It will be noted that in my iron the bottom of the water reservoir is separated by an air space from the top of the small boiler 35 and is separated by a larger space from the sole plate, hence little heat is transferred to the main body of water held in storage.

If it is desired to use the iron "dry," it is not necessary to empty the water from the iron; instead the operator merely turns knob 116 to lower closure valve 112 into sealing engagement with the outlet from the reservoir. Assuming the iron is in operation, the well 90 will boil dry in approximately 15 seconds, after which no further steam will be generated until valve 112 is again lifted.

To disassemble my iron for repair or servicing, knob 34 first is removed from shaft 30, then screws 82 are loosened and the rear cover plate 78 is removed. This exposes the electrical wiring, which has been omitted from the drawings for the sake of clarity, and gives access to screws 76. If the latter are unscrewed, skirt 72 may be taken off and screws 79 now can be loosened so that the upper portion of the iron (i.e. the water reservoir and handle) can be lifted free of the sole plate and its attached boiler. This renders all of the remaining parts readily accessible and the manner of completing the disassembly will be obvious. In remounting the water reservoir on the sole plate care should be taken to press the two together sufficiently to compress the O-ring 108 into sealing engagement, as shown, before tightening the screws 79.

From the foregoing it will be seen that this invention is one well adapted to obtain all of the ends and objects hereinbefore set forth, together with other advantages which are obvious and which are inherent to the apparatus. It is free of the various shortcomings of both the "tea kettle" type of iron and the "flash boiler" type, and in particular achieves all of the advantages of heating but a relatively small amount of water while at the same time avoiding the use of troublesome feed valves.

It will be understood that certain features and subcombinations are of utility and may be employed without reference to other features and subcombinations. This is contemplated by and is within the scope of the claims.

Inasmuch as various embodiments of the invention may be made without departing from the scope thereof, it is to be understood that all matter herein set forth or shown in the accompany-

ing drawings is to be interpreted as illustrative and not in a limiting sense.

Having thus described my invention, I claim:

1. In a steam iron, a sole plate, means for heating the sole plate, a boiler attached to the sole plate and overlying it, one of said boiler and sole plate elements being formed with a recessed portion to provide a well whereby the well is heated by said sole plate and heating means, a water reservoir having in its bottom an outlet duct extending downwardly into said well with an outlet opening spaced above the bottom but below the top of the well, the upper end of said duct being substantially flush with the bottom of said reservoir, baffle means in the reservoir around the mouth of the duct to prevent the water from surging across the mouth of the duct as the result of changes in the direction of the iron's movement, means for hermetically sealing said reservoir above the surface of the water therein, whereby water is fed automatically from the reservoir whenever the water level in said well drops below said outlet opening, and a steam outlet connected to said boiler.

15 2. In a steam iron, a sole plate, means for heating the sole plate, said sole plate having its upper surface recessed to form therein a shallow well of restricted horizontal cross section, a water reservoir having an outlet duct extending downwardly therefrom into said well with an outlet port spaced above the bottom but below the top of the well, means for hermetically sealing said reservoir above the surface of the water therein whereby the water is maintained at a sufficient depth in said well to cover said port baffle means in the reservoir around the mouth of said duct to prevent the water from surging across the mouth of the duct as the result of changes in the direction of the iron's movement, a dome over the surface of the water in said well for confining the steam generated by the heating thereof, said dome being positioned intermediate said reservoir and said sole plate, and a steam outlet passageway extending from the dome through the sole plate for conducting the steam onto the fabric being ironed.

20 3. In a steam iron, a sole plate, the upper surface of the sole plate being recessed to form therein a shallow well of restricted horizontal cross section, a U-shaped heating element embedded in the sole plate with its legs straddling said well, a water reservoir having an outlet duct extending downwardly therefrom into said well with the open lower end of the duct spaced below the top of the well, means for hermetically sealing said reservoir above the surface of the water therein whereby the water is maintained at a sufficient depth in the well to cover said open lower end of the duct, a dome over the surface of the water in said well confining the steam generated by the heating thereof, said dome being positioned intermediate said reservoir and said sole plate, and a steam outlet passageway extending from the dome through the sole plate for conducting the steam onto the fabric being ironed.

25 4. In a steam iron, a sole plate, a boiler attached to the sole plate and overlying it, one of said boiler and sole plate elements being formed with a recessed portion to provide a well, a water reservoir having in its bottom an outlet duct extending downwardly into said well with an outlet port spaced above the bottom but below the top of the well, the upper end of said duct being substantially flush with the bottom of said reservoir, baffle means in the reservoir around the

30 5. In a steam iron, a sole plate, a boiler attached to the sole plate and overlying it, one of said boiler and sole plate elements being formed with a recessed portion to provide a well, a water reservoir having in its bottom an outlet duct extending downwardly into said well with an outlet port spaced above the bottom but below the top of the well, the upper end of said duct being substantially flush with the bottom of said reservoir, baffle means in the reservoir around the

mouth of said duct to prevent the water from surging across the mouth of the duct as the result of changes in the direction of the iron's movement, means for hermetically sealing said reservoir above the surface of the water therein, means for heating the bottom and sides of the well thereby to convert into steam the water entering the well from the reservoir, and a steam passageway from the boiler extending through the sole plate for conducting the steam onto the fabric being ironed.

5. A steam iron as in claim 4 having a valve for said outlet duct, manually operable means for seating or unseating said valve at will to prevent or permit the flow of water through said duct, and means to automatically retain said valve in the position to which it was last operated.

6. In a steam iron, a sole plate, means for heating the sole plate, a boiler attached to the sole plate and overlying it, one of said boiler and sole plate elements being formed with a recessed portion to provide a well whereby the well is heated by said heating means and said sole plate, a water reservoir, means for detachably securing said reservoir to the sole plate above same and in vertically spaced relation thereto, an outlet duct integral with said reservoir extending downwardly through an aperture in the top of said boiler and into said well with its open lower end spaced below the top of the well, sealing means between the duct and the boiler closing said aperture around the duct, means for hermetically sealing said reservoir above the surface of the water therein.

7. In a steam iron, a sole plate, means for heating the sole plate, a boiler attached to the sole plate and overlying it, one of said boiler and sole plate elements being formed with a recessed portion to provide a well whereby the well is heated by said heating means and said sole plate, a water reservoir, means for detachably securing said reservoir to the sole plate above same and in vertically spaced relation thereto, the bottom of the reservoir and the top of the boiler having registering apertures, sealing means between the apertures forming a fluidtight passageway from the reservoir to the boiler when the reservoir is secured to the sole plate, a duct extending downwardly through the boiler into said well, the open upper end of the duct communicating with said reservoir through said passageway and the open lower end being spaced below the top of the well, said reservoir having a filler opening and a closure therefore, means for hermetically sealing said reservoir above the surface of the water when the filler opening is closed whereby water is maintained at a sufficient depth in said well to cover the open lower end of said duct.

8. In a steam iron, a sole plate, means for heating the sole plate, a boiler attached to the sole plate and overlying it, one of said boiler and sole plate elements being formed with a recessed portion to provide a well whereby the well is heated by said heating means and said sole plate, a water reservoir, means for detachably securing said reservoir to the sole plate above same and in vertically spaced relation thereto, the bottom of the reservoir and the top of the boiler having registering apertures, sealing means between the apertures forming a fluidtight passageway from the reservoir to the boiler when the reservoir is secured to the sole plate, a duct extending downwardly through the boiler into said well, the open upper end of the duct communicating with said reservoir through said passageway and the open

lower end being spaced below the top of the well, said reservoir having a filler opening and a closure therefore, means operable to open and close said passageway, means for hermetically sealing the reservoir above the surface of the water when the filler opening is closed whereby water is maintained at a sufficient depth in said well to cover the open lower end of said duct.

9. A steam generating device comprising a boiler, heating means for the boiler, a steam outlet for the boiler, a water reservoir above the boiler, a resilient annular gasket sandwiched between the bottom of the reservoir and the top of the boiler, a tension link connection between the reservoir and boiler forcibly clamping the two together and maintaining the gasket under compression, the bottom of the reservoir and the top of the boiler having aligned openings registering with the opening in said annular gasket whereby said gasket forms a fluidtight passageway from the reservoir to the boiler, a duct extending downwardly into the boiler, the open upper end of the duct communicating with the said reservoir through said passageway and the lower end of the duct being below the normal level of the water in the boiler, means for hermetically sealing said reservoir above the surface of the water therein whereby water is fed from the reservoir into the boiler when the level in the boiler drops below the opening at the lower end of the duct, and means for releasing said tension link connection to permit separation of the reservoir from the boiler.

10. A steam generating device comprising a base having a well adapted to contain water, means for heating the water in the well to produce steam, a cover carried by the base over the surface of the water for confining the steam, an outlet duct communicating with the steam space under the cover, means for automatically replenishing the water in said well as it is converted into steam; said last means comprising a water storage receptacle having an integral open neck of reduced cross section projecting from the bottom thereof, means removably supporting the receptacle on said base above said cover with said neck extending downwardly through an opening in the cover into said well and terminating above the bottom but below the top of the well, an annular gasket closely encircling said neck, the top of the gasket engaging the bottom of the receptacle and the bottom of the gasket engaging the top of said cover around said opening, said supporting means including releasable clamping connection between the base and reservoir compressing said gasket between the bottom of the reservoir and the top of the cover, whereby said gasket seals said opening around the neck, and means for hermetically sealing said receptacle above the surface of the water therein whereby water is automatically fed from the receptacle whenever the level in the well drops below the opening in the lower end of said neck.

11. In a steam iron of the type having a self contained reservoir carried by the sole plate, a horizontally disposed main reservoir section conforming in contour with the sole plate, a pair of laterally spaced posts upstanding from the top of said main section and carrying at their upper ends a hand grip spanning the space between the posts, both posts being hollow and having their interiors communicating with the interior of said main section to augment the water carrying capacity thereof, the upper end of one post being closed and the upper end of the other being open

11

to form a filler opening for the reservoir, a passageway extending from the upper end of said one post into said other post to permit escape of air during the filling of the reservoir, and a closure for said filler opening.

12. In a steam iron, a sole plate having heating means therein and a steam passageway therethrough, a boiler carried by the sole plate on the upper face thereof, one of said boiler and sole plate elements being provided with a recessed portion to provide a well, a transverse baffle upstanding from the floor of the boiler dividing the interior thereof into forward and rear sections, a stand pipe in the forward section of the boiler communicating with the steam passageway through the sole plate for conducting steam onto the fabric being ironed, the floor of the forward section of the boiler sloping rearwardly downward toward said baffle and the floor of the rear section being horizontal and substantially flush with the lowest point of said forward section, a drain passageway extending from the floor of the forward section past said baffle to the floor of the rear section to permit drainage of moisture from said sloping forward floor, a water storage reservoir, and flow control means to feed water from said reservoir into said well and

5

12

maintain the water level in the well substantially constant.

13. A steam iron as in claim 12 wherein the forward floor section of said boiler and sole plate are spaced from each other to provide an air space therebetween.

ROBERT J. SCOTT.
